UNITED STATES PATENT OFFICE.

JAMES A. EDEN, JR., OF SPRINGFIELD, MASSACHUSETTS, ASSIGNOR TO WALTER H. FOSTER, OF NEW YORK, N. Y.

STAYBOLT-MACHINE.

1,342,534.

Specification of Letters Patent. Patented June 8, 1920.

Application filed March 6, 1918. Serial No. 220,718.

To all whom it may concern:

Be it known that I, JAMES A. EDEN, Jr., a citizen of the United States, residing in Springfield, Massachusetts, have invented 5 certain new and useful Improvements in Staybolt-Machines, of which the following is a specification.

This invention aims to provide certain improvements in machines for threading and turning blanks to form staybolts such as are 10 commonly used in locomotive boilers.

The accompanying drawings illustrate an embodiment of the invention.

Figure 1 is a front elevation of the machine:

Fig. 2 is an elevation of a style of stay-bolt which may be made on the machine;

Figs. 3 and 4 are respectively a plan and 20 vertical section of a head for supporting the blank;

Fig. 5 is a side elevation of the tool holding carriage and the cutter head thereon;

Fig. 6 is a bottom plan thereof;

Fig. 7 is a vertical section on the line 7 25 indicated in Fig. 6;

Fig. 8 is a detail of a locking device intended to be substituted for that shown in Fig. 5 under certain conditions.

Referring to the particular embodiment 30 of the invention illustrated, the cutter head is mounted on the underside of the carriage A which is suspended from a cross-head B to which is attached a strap running over a pulley C on a slowly driven shaft over-head, the free end D of the strap being 35 within reach of the operator so that he can lift the carriage by pulling down the free end of the strap, the pulley C rotating in a direction to lift the carriage while the operator has only to hold the strap tight on 40 the pulley. A block or holder E is arranged on the table of the machine and has a squared hole F into which a squared end of the bolt blank is dropped. The carriage is 45 lowered onto the top of the bolt and allowed to press thereon by its weight. The block E is rotated while the cutters are held against rotation and the threads are cut and the intermediate part of the bolt turned 50 down by means of dies and cutters which are brought into operation at suitable points.

Most staybolts are headless and have the threads at opposite ends of uniform diameter 55 throughout. Special staybolts, however, are

required in particular locations which have their outer threaded ends tapered and I have illustrated such a bolt in Fig. 2 with an inner threaded end G of uniform diameter, an intermediate turned down portion H 60 and an outer end which is threaded and of uniform diameter over a portion J but of gradually enlarging diameter over the outer portion K. This bolt has a head L on which is a square projection M used for centering 65 it in the block E of the machine, but usually cut off after the bolt is set into the boiler. The present machine is designed for forming this special style of staybolt as well as the ordinary style.

The recessed block E which supports the lower end of the work is mounted on a shaft N journaled in bearings in a casing O passing through an opening of somewhat larger diameter in the supporting plate P of the 75 frame of the machine and carrying near its lower end a worm gear Q driven by a worm R on a shaft S which is rotated by any suitable means, and through which the overhead pulley C is also driven. The worm R 80 is mounted in split bearings consisting of an extension T from the casing O and a cap U which is bolted to the extension T. This construction is advantageous in permitting the ready removal of the casing O 85 with its shaft N. The block or head E at the upper end being unscrewed and the bolt V which fastens the casing on the plate P being also removed, it is only necessary to remove the cap U of the worm, whereupon, 90 by slightly tilting the casing O it can be lowered through the opening in the plate P for inspection and repair, if necessary.

Several styles of cutter heads are in use 95 which include the threading dies and the turning cutters. In all of them the operation is substantially as follows. The cutter head in its upper position carries the dies closed and bearing on the top of the blank; therefore, as the blank turns the dies engage 100 the work and cut a thread thereon from top to bottom. The turning tools are located in the same cutter head with the dies, at a point above the latter so that they follow the dies down. In the initial position the cutters are opened or separated so that they do not touch the work. At a determined 105 point in the downward travel of the head the cutters are closed or pressed inward so as to commence the turning of the reduced 110

shank of the bolt and at a later point they are withdrawn. This inward and outward movement of the tools is accomplished by cams and similar devices of various sorts 5 in different machines. The present invention is not involved with such control. At the end of its downward movement the head is operated by a stop fixed on the machine to withdraw or open the dies and to hold 10 them in this open position. They are thus clear of the work and the operator may lift the head quickly by the means above described and commence the making of a new bolt.

15 The die head or cutter head illustrated is of a known type in which the dies and cutters are pivotally mounted on a plate *W* carried on the underside of the carriage *A*, around which plate *W* is a ring *X* mounted 20 to turn and by its turning movement in one direction or the other to throw the dies and cutters inward or outward. Springs *Y* pull the ring *X* in the direction for opening the dies. On the outside of the ring *X* is 25 mounted in adjustable position a stop plate *Z* with a projection *a* adapted to be engaged by a pawl *b* pivotally mounted on the carriage *A*.

At the top of its movement a roller *x* on 30 the ring *X* strikes a cam *c* (Fig. 1) which throws the ring *X* around against the pull of its springs *Y* until the shoulder *a* catches under the pawl *b*, thus closing and locking the dies. At the lower end of the movement 35 of the carriage the pawl *b* strikes a stop *d*, Fig. 1, and is lifted off the shoulder *a*, whereupon the springs turn the ring *X* in a direction to open the dies. The mechanism whereby the turning of the ring opens and 40 closes the dies and holds them in the desired position is described hereinafter.

A point of improvement is in the means for producing at the bottom of the stroke a gradual turning of the ring and opening 45 of the dies so that they will produce the tapered thread *K*, Fig. 2; and for regulating the rate of such taper. For this purpose the engaging face of the projection or shoulder *a* is made of such inclination that as the 50 pawl *b* is gradually lifted there will be a small turning of the ring *X* in the direction of the arrow and thus a gradual separation of the thread cutting dies. The same result, of course, could be achieved by providing a tapered face for the pawl *b* and by 55 variously shaping the engaging faces of the parts *a* and *b*. The stop *d* is mounted in a bracket *e*, Fig. 1, and held by a set screw *f*, so that it can be adjusted in or out and will 60 strike the pawl *b* at a point nearer to or farther from its pivot and will thus cause a slower or faster turning of the ring *X* and consequent regulation of the rate of taper of the thread.

65 It has been previously proposed to mount

at a fixed point on the frame of the machine a wedge which would operate directly on the ring *X* so as to gradually turn the latter and cause a taper of the thread. But when a thread of different taper has been 70 required a new wedge has had to be substituted. By the use of the pawl *b* and the adjustable stop *d* it becomes very easy to change the taper as required for different classes of work. The stop *d* might in fact 75 be arranged so close to the pivot of the pawl *b* as to lift the latter almost instantaneously and to stop the thread with practically no taper.

For producing the ordinary withdrawal 80 of the dies, where the thread is not to be tapered a die plate *Z'*, Fig. 8, may be substituted, having its projection *a'* so shaped that there will be no movement until the pawl *b* entirely clears the projection. 85

The threading dies or chasers, of which one is indicated in section at *g*, Fig. 7, are mounted in blocks *h* supported by pivots *j* from the plate *W*. Toggle links *k* are connected at their outer ends to the ring *X* and 90 at their inner ends to the blocks *h* and are set at such an angle that the movement of the ring by the springs will pull the dies away from the work indicated at *K*, in Fig. 6, and the movement in the opposite direction will thrust the dies forcibly against the work. These links *k* are set in the lower 95 parts of the ring *X* and blocks *h* so as to resist any tendency to tilt the blocks *h* by the backward reaction from the work. The construction is very simple and holds the dies firmly to the work and evenly throughout 100 their length.

The means described for producing a tapered thread may be applied to the manufacture of various other bolts than the stay-bolts specified, as also may the toggle arrangement for opening and closing the dies. In fact, the improvements generally are applicable to a variety of machines other than 110 that illustrated and may be modified in detail and arrangement by persons skilled in the art without departing from the invention.

No claim is made to the toggle arrangement in the present application. Such an arrangement being shown with slight modifications in my application No. 271,631 and being claimed there. 115

What I claim is—

1. A machine for threading staybolts or the like comprising a carriage, a die carrying head mounted thereon and having a movable part which controls the opening of the dies and an adjustable stop adapted 125 to strike said movable part at different points and thus to vary the rate of opening of the dies.

2. A machine for threading staybolts or the like comprising a carriage, a die carry- 130

- ing head mounted thereon having spring-
actuated means for opening the dies and hav-
ing a pawl which holds the dies closed and
permits them to open gradually as the pawl
5 is withdrawn and an adjustable stop adapted
to engage said pawl at different points to
withdraw it at different rates and to cause
the gradual opening of the dies at different
rates.
- 10 3. A machine for threading staybolts and
the like including in combination a die car-
rying head having a spring actuated ring
X which controls the adjustment of the dies
a stop α on said ring and a pawl engaging
15 said stop, the engaging faces of said stop and
pawl being shaped to produce a gradual

opening of the dies as the pawl is progres-
sively withdrawn.

4. A machine for threading staybolts and
the like comprising a bolt carrier, a shaft 20
N for the same and a casing O carrying
bearings in which said shaft is mounted, a
worm gear on said shaft, a worm engaging
said gear and mounted in bearings compris-
ing a projection from said casing and a 25
movable cap, said casing O passing through
an opening in a plate P so that by removal
of said cap said casing, shaft and worm gear
can be withdrawn as a unit.

In witness whereof, I have hereunto signed 30
my name.

JAMES A. EDEN, JR.
